CLAIM

The ornamental design for an decal for identification of an LED indicator on a desktop computer, as shown and described.

DESCRIPTION

FIG. 1 is a front elevational view of the decal for identification of an LED indicator on a desktop computer showing my new design, the computer being shown in broken lines for illustrative purposes only; and, FIG. 2 is an enlarged front elevational view thereof, it being understood that the decal is flat with no substantial thickness.

Fig. 1

Fig. 2
